COLLAPSIBLE DISPENSING TUBE

Charles L. Weckesser, 20 Hayes St., Norwich, N.Y.

Filed July 18, 1960, Ser. No. 61,396

Term of patent 14 years

(Cl. D58—17)

FIG. 3

FIG. 1

FIG. 2

FIG. 4

FIGURE 1 is a front elevational view of a collapsible dispensing tube, showing my new design;

FIGURE 2 is a side elevational view thereof;

FIGURE 3 is a top plan view thereof; and

FIGURE 4 is a bottom plan view thereof.

The rear and side not shown are the same as the respective front and side shown.

I claim:

The ornamental design for a collapsible dispensing tube, as shown and described.
